United States Patent Office

Des. 211,825

Patented July 30, 1968

211,825

INDUSTRIAL GAS WASHING DEVICE

George Howard Willett, Jr., 655 Pilgrim,
Birmingham, Mich. 48009

Filed Oct. 2, 1967, Ser. No. 8,824

Term of patent 14 years

(Cl. D49—11)

FIG. 1

FIG. 2

FIG. 3

FIG. 1 is a perspective view of the industrial gas washing device, embodying my new design.

FIG. 2 is a side elevational view thereof.

FIG. 3 is an end view thereof.

I claim:

The ornamental design for an industrial gas washing device, as shown.
